UNITED STATES PATENT OFFICE.

WILLIAM C. FREE, OF CHICAGO, ILLINOIS.

SHUTTLE-DRIVING MECHANISM FOR SEWING-MACHINES.

SPECIFICATION forming part of Letters Patent No. 692,842, dated February 11, 1902.

Application filed May 27, 1901. Serial No. 62,154. (No model.)

To all whom it may concern:

Be it known that I, WILLIAM C. FREE, a citizen of the United States of America, residing at Chicago, in the county of Cook and State 5 of Illinois, have invented certain new and useful Improvements in Shuttle-Driving Mechanisms, of which the following is a specification.

My invention relates specifically to mechanism for driving the shuttles of sewing-machines.

Its object is the production of a simply and compactly constructed and easily-operated mechanism for driving the shuttles of such 15 machines by oscillation; and it consists of certain new and useful features of construction and combinations of parts especially devised for those ends, all as hereinafter fully described, and specifically pointed out in the 20 claim.

Referring to the accompanying drawings, which form a part of this specification, Figure 1 is a bottom plan view of a sewing-machine provided with my improvements. Fig. 25 2 is a section at the dotted line 2 2 in Fig. 1 of parts there shown. Fig. 3 is a side elevation of the shuttle-driving mechanism shown in Fig. 1. Fig. 4 is a section at the dotted line 4 4 in Fig. 3 of parts there shown. Figs. 30 5 and 6 are bottom plan views of the shuttle-driving mechanism, showing the positions the parts thereof assume when the shuttle-carrier is at the two extremes of its travel. Fig. 7 is an end view of the gimbal-ring and 35 a cross-section of the driving-shaft of the shuttle-driving mechanism.

Like letters of reference indicate corresponding parts throughout the several views.

A is the base-plate of a sewing-machine 40 and is provided with downwardly-projecting lugs A¹ A², having bearings A³ A⁴ therein for supporting a part to be described hereinafter.

B is an oscillatory-shuttle-carrier driver mounted on a pivot B⁴ on the base-plate A, 45 provided at its upper end with a transversely-projecting arm B⁵ to support a shuttle-carrier, and terminating at its lower end in bifurcations B⁶, having transverse bearings B⁷ therein.

50 B⁸ is a bushing, B⁹ a bushing-retaining screw, and B¹⁰ a set-screw, which together serve to retain the oscillatory shuttle-carrier driver adjustably on its supporting-pivot B⁴.

C is a gimbal-ring mounted by means of trunnions C' thereon in the bearings B³ in 55 the shuttle-carrier driver B.

D is a driving-shaft passing through the opening C² in the gimbal-ring C and mounted in bearings A³ A⁴ in the lugs A¹ A².

E is a collar fast to the driving-shaft D, 60 having an inclined driving-face E' thereon, which is in a plane oblique to the longitudinal axis of the driving-shaft D, whereby the adjacent face C³ of said gimbal-ring is held substantially parallel to and in contact with the 65 inclined end E' of such collar E.

E² is a shuttle-carrier of any desired form and construction, secured to or integral with a shuttle-carrier-driver arm B'.

F is a wrist-wheel fast to the driving-shaft 70 D and provided with a wrist-pin F'.

F² is an eccentric-rod connecting the wrist-pin F' of the wrist-wheel F with an eccentric (not shown) on the main shaft (also not shown) of the machine.

75 Each rotation by the driving-shaft D of the collar E, acting upon and through the gimbal-ring C, will drive the shuttle-carrier E² and its shuttle (not shown) through a complete oscillation or back-and-forth movement, as indicated by the dotted double arrow in Fig. 1 and as shown by Figs. 5 and 6.

What I claim as new, and desire to secure by Letters Patent, is—

In a shuttle-driving mechanism for sewing-machines, in combination, an oscillatory-shuttle-carrier driver, a gimbal-ring mounted in bearings therein, a driving-shaft passing through the gimbal-ring, a collar—fast to the driving-shaft—having a driving-face thereon 85 which is in a plane oblique to the longitudinal axis of said driving-shaft, whereby the adjacent face of said gimbal-ring is held substantially parallel to, and in contact with, the inclined end of said collar, and means for 90 driving said shaft, substantially as and for the purpose specified.

In testimony whereof I have signed my name to this specification in the presence of two subscribing witnesses.

WILLIAM C. FREE.
